General Designs -

FIG. 1. Design. FIG. 2

No. 1,241.

Des. 1241

J. M. Gibney of New York, N.Y.
Letters Patent No 1241. Dated May 15. 1860

The schedule referred to in these Letters Patent and making part of the same.

To all whom it may concern:

Be it Known that J. M. Gibney, of the City, County and State of New York, have invented or produced a new and ornamental design for ornamenting the handles of Forks, Spoons, or other articles of table ware and cutlery, whether made of Silver or other metal, and I do hereby declare the following to be a full description of the same, reference being had to the accompanying drawings forming a part of this Specification, the same letters of reference wherever they occur referring to like parts.

Figure 1. is the front side of the fork.

2. is the back . . . it .

Letter a, is the shield of the front side of the fork, the upper end of which is shaped or pointed somewhat like a Gothic Arch, while the sides at the point of connection with the head, b. of the handle c, is contracted so as to give a curved outline, to preserve the harmony and length of the design for the shield.

Around the upper edge of the shield, is an external flat thread

d, which terminates at the broadest part of the shield in a scroll e. Inside of this outer thread are two thin threads, which commence at the apex of the shield and loose themselves in the same. Descending from the apex towards the center of the shield are two fleur d'lis devices f, supported one upon the other, and from the point of the lowermost one, are two small head like points, surrounding the lower sides of the shield in a branch or continuation of the external flat thread d, the ends of which form a scroll g, meeting on the head b, at each side of a star like device h, the rays of which terminate in five beads, having a scolloped bordering. The head b, represents (on the front side of the shield) an intermediate device between the shield and ... handle. In the center of it at the point where it joins the shield is a five leaved shell i, in the upper or center part of which is the knotted ends of two threads j, which branching outwards, form marginal threads around the head, and terminate in scrolls at the juncture of the head with the handle.

From the center leaf of the shell like ornament descends a drop k, on the head of which is a fleur d'lis l, having four vanishing points m, descending down the middle of the handle. On the edges of the handle, is a raised double thread n, commencing at the upper end of the handle in a reversed leaf like device p, and terminating at the shank, in a five pointed leaf q, having a raised stem extending up the middle of the handle, to complete the general design for the front side of the fork.

Letter a, is the shield of the reverse side of the fork, which is externally shaped like the front side. Surrounding the margin of it, and the head b, are two raised threads r, and an inner thread s, with an intervening concave space between it and the threads r. At the apex of the shield the threads s, are united by a fleur d'lis but at the lower end of the shield where it joins on to the head of the handle, all the threads unite in a scroll like device t, at each side of a star like ornament u, radiating down the handle, with terminal points or beads at the ends of the rays. Below the star is a fleur d'lis v, having descending from its middle leaf five vanishing points. Surrounding the margin of the handle are three raised threads w, commencing at the head of the handle in a scroll at each side of the device t, and terminating in a scroll x, at each side of a broad three pointed leaf y, covering the shank of the fork, the stem of which forms a raised oval center

up the middle of the handle, to complete the ornamental device for the reverse side of the fork.

Having now described my new design for ornamenting the handles of Forks, Spoons and other articles of table ware and cutlery, whether made of Silver or other metal. I will proceed to set forth what I claim and desire to secure by Letters Patent of the United States.

What I claim is the application and use of the combination and arrangement of the ornamental devices for the purpose of ornamenting the obverse, or reverse sides of forks, spoons, or other articles of table ware and cutlery, whether made of Silver or other material or metal.

Witnesses.

Addison Brown,
Charles L. Barrett.

M. Gibney.
